US0D1058897S

(12) **United States Design Patent** (10) Patent No.: **US D1,058,897 S**
(45) Date of Patent: ** Jan. 21, 2025

(54) **LED LIGHTING APPARATUS**

(71) Applicant: **Chung Han Yu**, City of Industry, CA (US)

(72) Inventor: **Chung Han Yu**, City of Industry, CA (US)

(**) Term: **15 Years**

(21) Appl. No.: **29/832,203**

(22) Filed: **Mar. 25, 2022**

(51) LOC (15) Cl. **26-05**

(52) U.S. Cl.

USPC **D26/85**

(57) **CLAIM**

The ornamental design for an LED lighting apparatus as shown and described.

DESCRIPTION

FIG. 1 is a top perspective view of an LED lighting apparatus;

FIG. 2 is a front plan view of the LED lighting apparatus; FIG. 3 is a rear plan view of the LED lighting apparatus; FIG. 4 is a side elevational view of the LED lighting apparatus;

FIG. 5 is another side elevational view of the LED lighting apparatus;

FIG. 6 is a top plan view of the LED lighting apparatus; and, FIG. 7 is a bottom plan view of the LED lighting apparatus. The broken lines depict portions of the LED lighting apparatus and that form no part of the claimed design.

1 Claim, 6 Drawing Sheets
